HYPODERMIC SYRINGES

Seymour N. Blackman, Teaneck, N. J., assignor to Omega Precision Medical Instrument Co., Inc., Passaic, N. J., a corporation of New Jersey

Application June 24, 1957, Serial No. 667,633

14 Claims. (Cl. 128—218)

This invention relates to hypodermic syringes. As is well known, the needles of hypodermic syringes conventionally are removed for sterilization after each use. In addition, the needles occasionally are sharpened, and for different purposes different sized needles must be employed. The foregoing necessitates the use of sterilizing and sharpening equipment which is both costly and time-consuming to use. Still further, needles of many different sizes must always be kept ready to use.

It is an object of the present invention to provide a syringe which will obviate the need for field sterilization and sharpening equipment and for resterilization of a needle after use.

It is another object of the present invention to provide a syringe of the character described in which a needle of a given length has several predetermined effective lengths, so that the syringe can be used for the different purposes for which different sized needles are required without changing the needles.

It is another object of the present invention to provide a syringe of the character described which is sturdy and long-lasting.

It is another object of the present invention to provide a syringe of the character described which is smooth-working and simple to use and inexpensive to manufacture.

It is another object of the present invention to provide a syringe of the character described in which a resilient piston located in a disposable barrel is uniquely couplable with an actuating stem in a manner such that the interengagement and disengagement of the stem and barrel is completely automatic.

It is another object of the present invention to provide a syringe of the character described in which the resilient piston and the actuating stem are so mutually constructed that, regardless of the material of the piston, the sides thereof will press against the walls of the barrel with a force sufficient to enable a substantial hydrostatic pressure to be developed in the syringe.

It is an ancillary object of the present invention to provide a syringe of the character described having a disposable needle-carrying barrel which can be located in any of a plurality of predetermined positions with respect to a reusable frame.

Other objects of the invention will be in part obvious and in part will be pointed out hereinafter.

The invention accordingly consists in features of construction, combinations of elements and arrangements of parts which will be exemplified in the hypodermic syringe hereinafter described and of which the scope of application will be indicated in the appended claims.

In the accompanying drawings, in which is shown one of the various possible embodiments of the invention,

Fig. 1 is an exploded perspective view of a syringe constructed in accordance with the instant invention;

Fig. 2 is an assembled perspective view thereof;

Fig. 3 is a sectional view taken substantially along the

2

line 3—3 of Fig. 2 and showing the stem adjacent to but uncoupled from the piston;

Fig. 4 is a fragmentary view similar to Fig. 3 but illustrating the piston coupled to the stem;

Fig. 5 is a sectional view taken substantially along the line 5—5 of Fig. 2;

Fig. 6 is a sectional view taken substantially along the line 6—6 of Fig. 3; and

Fig. 7 is a top view of the piston.

Referring now in detail to the drawings, the reference numeral 10 denotes a hypodermic syringe constructed in accordance with the instant invention. Said syringe includes two parts, to wit, a reusable frame 12 and a disposable needle-carrying barrel 14. The barrel preferably is fabricated from a pellucid synthetic and desirably a plastic which is heat sterilizable, e. g., a polyamide resin. The barrel has an open rear end 16 and a closed front end 18. The latter includes a through opening 20 in which the base of a hypodermic needle 22 is tightly permanently secured. Diametrically opposite radially projecting ears 24 are formed on each side of the barrel adjacent the front end thereof.

Each barrel includes a resilient cup-shaped piston 26 fabricated, for example, from a natural or synthetic rubber or a pliable plastic such, for instance, as polyethylene. The forward end of the piston is closed and the rear end open. When the barrel is sold, the piston is located in its open rear end as shown in Fig. 3. Pursuant to a feature of the invention, said piston includes laterally outwardly extending integral protuberances, e. g., flanges 28, projecting from adjacent the rear end beyond the wall of the barrel. Desirably the side walls of the piston are externally annularly ribbed.

The reusable frame preferably is fabricated from metal, e. g. stainless steel, although it can be made of a durable hard plastic, such as a polyamide resin. The frame comprises a front end wall 30, a fragmentary bottom wall 32 and a pair of curved side walls 34, 36 spaced apart a distance sufficient for the barrel to be received between them. The side walls are joined at their tops by a tubular head section 38 located at the rear end of the frame. The head section includes a cap 40 from which finger flanges 42 extend.

The bottom wall has a forward opening 44 and the front wall a central opening 45, the two openings being connected by a wedge-shaped slot 46 in the front wall. A series of bayonet slots 48 is provided along the upper edge of each side wall, each slot in one side wall being registered with a slot in the other side wall. The bayonet slots include upwardly extending vertical portions 50 and forwardly extending horizontal portions 52. The latter portions are non-circular in cross section and are so dimensioned as to be capable of snugly slidably and non-rotatably receiving the ears 24 of the barrel. Desirably the ears and portions 52 likewise have rectangular cross-sections.

A stem 54 fabricated, for example, from metal is journaled for axially slidable movement in the cap 40, a bearing 56 being provided in the cap to guide the stem for forward and rearward movement. The plunger includes a thumbrest 60 at the rear end thereof and a disc 62 at the front end. Said disc has a slightly larger diameter and lesser length than the cup formed by the piston 26 in the rear end of the barrel. The reason for this will be apparent hereinafter.

The syringe is assembled by fitting the barrel into the frame. This is done by holding the barrel with the needle pointing downwardly and forwardly and then inserting the ears 24 into the vertical portions 50 of any selected pair of registered bayonet slots 48. During this operation the needle passes through the opening 44. Next the barrel is swung about the ears 24 to bring its

longitudinal axis and that of the frame into coincidence, the needle 22 first traversing the slot 46 and then entering the opening 45 during this operation. Now the barrel is shifted forwardly to bring the ears against the bottom of the slots 48.

The next step is to move the stem forwardly until the disc 62 thereof abuts the bottom of the piston.

To complete assembly of the syringe, the stem is moved further forwardly to lock the disc 62 to the piston. Continued forward movement of the stem causes the piston to move forwardly, pulling the flanges 28 into the barrel. The latter is not large enough to accommodate the flanges so that the flanges swing or are compressed into the barrel behind the disc, as shown in Fig. 4. Due to this arrangement it is impossible accidentally to pull the piston out of the barrel.

Attention is directed to the slightly oversize diameter of the disc 62. The piston 26 is a snug fit in the barrel. However, repeated sterilization may somewhat lower the resiliency of the material of which it is composed. Moreover, when the piston is fabricated from polyethylene, it tends, after a time, to lessen its pressure against the barrel walls. Both of these difficulties are counteracted by the oversize disc which each time it enters the piston expands the same against the barrel.

The barrels are furnished empty and their needles are in sterile condition. The needles are protected against contamination in any conventional way, as by furnishing the entire barrel, including the needle, in an air-tight container or by disposing a sleeve over the needle alone. When it is desired to use the syringe, a barrel is selected and assembled to the carrier as described above. The stem is pushed all the way forward, the needle is inserted into the medicament and the stem pulled back until sufficient medicament has been sucked up into the barrel. The medicament is injected into the patient in the usual manner.

After a single use the barrel is discarded. To do this, the stem is withdrawn as far as it will go so that the disc is automatically uncoupled from the piston. The barrel then is tilted by pushing the back upwardly, and the barrel is withdrawn from the frame.

It will be apparent from the foregoing that a convenient and simple construction has been provided whereby the costly and time-consuming field sterilizing and sharpening of hypodermic syringe needles is completely eliminated.

The provision of a plurality of pairs of registered bayonet slots in the frame enables the user of the syringe to vary the effective length of the needle in accordance with the requirements of the use to which the syringe is to be put. Thus, a barrel having a needle with a fixed length can be disposed and locked in various positions in the frame whereby the effective length of the needle, i. e., the length projecting from the front end of the frame, is different. The number of different effective lengths for any given actual length of needle will be controlled by the number of different pairs of registered bayonet slots. Moreover, the distance between adjacent slots can be varied and need not be the same for each adjacent pair of slots.

It thus will be seen that there is provided a hypodermic syringe which achieves the several objects of the invention and is well adapted to meet the conditions of practical use.

As various possible embodiments might be made of the above invention, and as various changes might be made in the embodiment above set forth, it is to be understood that all matter herein described, or shown in the accompanying drawings, is to be interpreted as illustrative and not in a limiting sense.

Having thus described the invention, there is claimed as new and desired to be secured by Letters Patent:

1. A hypodermic syringe comprising a disposable barrel having an open end and a closed end with a through aper-

ture, a hypodermic needle permanently secured to the closed end of the barrel with an end thereof in said aperture, said end having a bore communicating with the interior of the barrel, an elongated reusable frame including a handle end and a front end, cooperating means associated with said barrel and frame for detachably mounting said barrel in said frame in selectable positions along the longitudinal axis of the frame with said open end remote from the front end of the frame, a piston in said barrel, a stem mounted in the handle end of the frame for movement longitudinally of the frame, and cooperating means associated with the piston and stem for releasably coupling the stem to the piston.

2. A hypodermic syringe comprising a disposable barrel having an open end and a closed end with a through aperture, a hypodermic needle permanently secured to the closed end of the barrel with an end thereof in said aperture, said end having a bore communicating with the interior of the barrel, an elongated reusable frame including a handle end and a front end, cooperating means associated with said barrel and frame for detachably mounting said barrel in said frame in selectable positions along the longitudinal axis of the frame with said open end remote from the front end of the frame, the part of 15 said means associated with the barrel comprising diametrically opposite radially projecting ears on the barrel adjacent the closed end thereof, and the part of the means associated with the frame comprising a series of angled slots disposed longitudinally of the frame on each side 20 thereof, each slot on one side being registered with a slot on the other side, a piston in said barrel, a stem mounted in the handle end of the frame for movement longitudinally of the frame, and cooperating means associated with the piston and stem for releasably coupling 25 the stem to the piston.

3. A hypodermic syringe comprising a disposable barrel having an open end and a closed end with a through aperture, a hypodermic needle permanently secured to the closed end of the barrel with an end thereof in said aperture, said end having a bore communicating with the interior of the barrel, an elongated reusable frame including a handle end and a front end, cooperating 40 means associated with said barrel and frame for detachably mounting said barrel in said frame in selectable positions along the longitudinal axis of the frame with said open end remote from the front end of the frame, the part of said means associated with the barrel comprising diametrically opposite radially projecting ears on the barrel adjacent the closed end thereof, and the part of the means associated with the frame comprising a series of angled slots disposed longitudinally of the frame on each side 45 thereof, each slot on one side being registered with a slot on the other side, said angled slots including upwardly extending vertical portions and frontwardly extending horizontal portions, a piston in said barrel, a stem mounted in the handle end of the frame for movement longitudinally of the frame, and cooperating means associated with the piston and stem for releasably coupling the stem to the piston.

4. A hypodermic syringe comprising a disposable barrel having an open end and a closed end with a through aperture, a hypodermic needle permanently secured to the closed end of the barrel with an end thereof in said aperture, said end having a bore communicating with the interior of the barrel, an elongated reusable frame including a handle end and a front end, cooperating means associated with said barrel and frame for detachably mounting said barrel in said frame in selectable positions along the longitudinal axis of the frame with said open end remote from the front end of the frame, an elastomeric piston in said barrel, a stem mounted in the handle end of the frame for movement longitudinally of the frame, said piston including laterally outwardly extending protuberances projecting beyond the wall of 55 the barrel from adjacent the rear end thereof when the 60

piston and stem are in uncoupled condition, said stem having an end facing the piston, said end having a diameter less than the inner diameter of the barrel whereby on forward movement of the stem said facing end abuts the piston and moves the same forwardly in the barrel and entry of the protuberances into the barrel releasably locks said end of the stem to the piston without relative rotation of the piston and stem.

5. A hypodermic syringe comprising a disposable barrel having an open end and a closed end with a through aperture, a hypodermic needle permanently secured to the closed end of the barrel with an end thereof in said aperture, said end having a bore communicating with the interior of the barrel, an elongated reusable frame including a handle end and a front end, cooperating means associated with said barrel and frame for detachably mounting said barrel in said frame in selectable positions along the longitudinal axis of the frame with said open end remote from the front end of the frame, an elastomeric piston in said barrel, a stem mounted in the handle end of the frame for movement longitudinally of the frame, said piston including laterally outwardly extending protuberances projecting beyond the wall of the barrel from adjacent the rear end thereof when the piston and stem are in uncoupled condition, said stem having an end facing the piston, said end having a diameter less than the inner diameter of the barrel and being laterally engaged by the piston when the protuberances of the piston are directed inwardly upon engagement of the protuberances with the barrel as the piston moves forwardly therein, whereby on forward movement of the stem, the stem and piston automatically are coupled and are automatically uncoupled on reverse movement of the stem when the piston reaches the open end of the barrel.

6. A hypodermic syringe comprising a disposable barrel having an open end and a closed end with a through aperture, a hypodermic needle permanently secured to the closed end of the barrel with an end thereof in said aperture, said end having a bore communicating with the interior of the barrel, an elongated reusable frame including a handle end and a front end, cooperating means associated with said barrel and frame for detachably mounting said barrel in said frame in selectable positions along the longitudinal axis of the frame with said open end remote from the front end of the frame, an elastomeric piston in said barrel, a stem mounted in the handle end of the frame for movement longitudinally of the frame, said piston including laterally outwardly extending protuberances projecting beyond the wall of the barrel from adjacent the rear end thereof when the piston and stem are in uncoupled condition, said stem including a head facing the piston, said head having a diameter less than the inner diameter of the barrel, whereby on forward movement of the stem the head abuts the piston and moves the same forwardly in the barrel and entry of the protuberances into the barrel releasably locks the head to the piston.

7. A hypodermic syringe comprising a disposable barrel having an open end and a closed end with a through aperture, a hypodermic needle permanently secured to the closed end of the barrel with an end thereof in said aperture, said end having a bore communicating with the interior of the barrel, an elongated reusable frame including a handle end and a front end, cooperating means associated with said barrel and frame for detachably mounting said barrel in said frame in selectable positions along the longitudinal axis of the frame with said open end remote from the front end of the frame, a cup-shaped elastomeric piston in said barrel, a stem mounted in the handle end of the frame for movement longitudinally of the frame, the open end of said piston facing the handle end of said frame, said piston including laterally outwardly extending protuberances projecting beyond the wall of the barrel from adjacent the open end

thereof when the piston and stem are in uncoupled condition, said stem including a disc at the end thereof facing the piston, said disc having a lesser length than the inner length of the cup formed by the piston and being receivable in the cup on forward movement of the stem, whereby on forward movement thereof the disc abuts the closed end of the piston and moves the same forwardly in the barrel and entry of the protuberances into the barrel releasably locks the disc to the piston.

8. A hypodermic syringe comprising a disposable barrel having an open end and a closed end with a through aperture, a hypodermic needle permanently secured to the closed end of the barrel with an end thereof in said aperture, said end having a bore communicating with the interior of the barrel, an elongated reusable frame including a handle end and a front end, cooperating means associated with said barrel and frame for detachably mounting said barrel in said frame in selectable positions along the longitudinal axis of the frame with said open end remote from the front end of the frame, a cup-shaped elastomeric piston in said barrel, a stem mounted in the handle end of the frame for movement longitudinally of the frame, the open end of said piston facing the handle end of said frame, said piston including laterally outwardly extending protuberances projecting beyond the wall of the barrel from adjacent the open end thereof when the piston and stem are in uncoupled condition, said stem having a head facing the piston, said head having a lesser diameter than the inner diameter of the barrel, the side wall of said piston having a greater thickness than the difference between the diameter of the head and the inner diameter of the barrel, whereby on forward movement of the stem the head abuts the piston and moves the same forwardly in the barrel and entry of the protuberances into the barrel releasably locks the head to the piston, and said piston is expanded against the inner wall of the barrel so as to be snugly contained therein.

9. In a hypodermic syringe, a barrel having an open end, an elongated frame in which the barrel is detachably receivable, an elastomeric piston in said barrel, a stem mounted at the back of the frame for movement longitudinally of the frame, and means releasably coupling the piston to the stem, said means comprising laterally outwardly extending protuberances projecting beyond the wall of the barrel from adjacent the open end thereof when the piston and stem are in uncoupled condition, said means further comprising an end of said stem facing the piston and having a diameter less than the inner diameter of the barrel, whereby on forward movement of the stem, the stem and piston automatically are coupled and are automatically uncoupled on reverse movement of the stem when the piston reaches the open end of the barrel.

10. In a hypodermic syringe, a barrel having an open end, an elongated frame in which the barrel is detachably receivable, a cup-shaped elastomeric piston in said barrel, a stem mounted at the back of the frame for movement longitudinally of the frame, and means releasably coupling the piston to the stem, said means comprising laterally outwardly extending protuberances projecting beyond the wall of the barrel from adjacent the open end thereof when the piston and stem are in uncoupled condition, said means further comprising a head on said stem facing the piston and having a diameter less than the inner diameter of the barrel, the side wall of said piston having a greater thickness than the difference between the diameter of the head and the inner diameter of the barrel, whereby on forward movement of the stem the head abuts the piston and moves the same forwardly in the barrel and entry of the protuberances into the barrel releasably locks the head to the piston, and said piston is expanded against the inner wall of the barrel so as to be snugly contained therein.

11. For use with a hypodermic syringe including an

elongated reusable frame including a handle end and a front end, a disposable barrel having a closed end with a through aperture, a hypodermic needle permanently secured to said end of the barrel with an end thereof in said aperture, said needle having a bore communicating with the interior of the barrel, a stem mounted in the handle end of the frame for movement longitudinally of the frame, and means on said barrel cooperable with means on said frame for detachably mounting the barrel in selectable positions along the longitudinal axis of the frame, the needle projecting from the front end of the frame in all positions of the barrel in the frame.

12. For use with a hypodermic syringe including an elongated reusable frame including a handle end and a front end, a disposable barrel having a closed end with a through aperture, a hypodermic needle permanently secured to said end of the barrel with an end thereof in said aperture, said needle having a bore communicating with the interior of the barrel, a stem mounted in the handle end of the frame for movement longitudinally of the frame, and diametrically opposite radially projecting ears on said barrel cooperable with means on said frame to detachably mount the barrel in selectable positions along the longitudinal axis of the frame, the needle projecting from the front end of the frame in all positions of the barrel in the frame.

13. For use with a hypodermic syringe including a disposable barrel having a closed end with a through aperture and a hypodermic needle permanently secured to said closed end of the barrel with an end thereof in said aperture, said needle having a bore communicating with the interior of the barrel: an elongated reusable frame including a handle end and a front end, a stem mounted in the handle end for movement longitudinally

5 of the frame, and means associated with the frame and cooperable with means associated with said barrel for detachably mounting said barrel in said frame in selectable positions along the longitudinal axis of the frame, the needle projecting from the end of the frame in all positions of the barrel in the frame.

14. For use with a hypodermic syringe including a disposable barrel having a closed end with a through aperture, said barrel having diametrically opposite radially projecting ears, and a hypodermic needle permanently secured to said closed end of the barrel with an end thereof in said aperture, said needle having a bore communicating with the interior of the barrel: an elongated reusable frame including a handle end, a front end and a tubular side wall having a wide longitudinal slot, a stem mounted in the handle end of the frame for movement longitudinally of the frame, said frame also including a series of separate narrow angled slots disposed longitudinally of the frame on each side thereof and communicating with the edges of the wide slot for snugly receiving said ears, each narrow slot on one side being registered with a narrow slot on the other side, said registered narrow slots cooperating with said ears to detachably mount the barrel in said frame in selectable positions along the longitudinal axis of the frame, the needle projecting from the front end of the frame in all positions of the barrel in the frame.
